FIG. 7.

UNITED STATES PATENT OFFICE

2,027,320

ILLUMINATED SIGN

William B. Piper, Memphis, Tenn., assignor to
Gasmold Sign Corporation, Memphis, Tenn., a
corporation of Tennessee

Application September 27, 1934, Serial No. 745,809

11 Claims. (Cl. 40—130)

My invention relates to an illuminated sign, of the type using neon and similar electrically energized bright colored gases and has for its object the production of insignia, such as raised letters, 5 numbers and other irregular objects from glass, by molding such insignia, thereby making quantity production feasible.

Most of the signs of this type now in commercial use are made from glass tubing which has to 10 be bent to the desired shape and this method does not lend itself readily to cheap quantity production.

A further object is to provide hollow molded glass insignia, having such a structure that every 15 portion can be illuminated.

Referring to the drawings for a more complete disclosure of the invention,

Fig. 1 is a front view of a completed box shaped sign,
20 Fig. 2 is a rear view of Fig. 1 with a fragment of the back plate of the box removed,

Fig. 3 is a vertical transverse section of a slightly modified form, comparable in part to a section along the line 3—3 of Fig. 1,

25 Fig. 4 is a fragmentary horizontal section along the line 4—4 of Fig. 1,

Fig. 5 is a fragmentary section along the line 5—5 of Fig. 1,

Fig. 6 presents a group of views of various letters showing the path of the illuminating gas, and
30

Fig. 7 is a section of a modified form with two gas tubes for different colored gases.

Each letter 1, when assembled forms a complete unit and is provided with a positive and negative 35 electrode 2 and 3, suitably connected to a high frequency transformer 4, the various units of the sign being electrically connected in series. A permanent sign of the type shown in Fig. 1 is made by clamping each unit 1 in the box 5 by 40 means of the strips 6, secured to the top and bottom of the box 5 by bolts.

The construction shown in Fig. 3, is particularly adapted for signs, the letters of which are 45 changed from time to time, as in theater marquees. Here each illuminated unit 1, is supported in a closed box 5 and provided on the back, with a glass or porcelain plate 7.

In making the letters 1, which have a hollow 50 channel 13 for the illuminating gas, I provide a separate mold for each type of letter. In order to completely illuminate every loop or branch of certain letters, it is necessary to locate the electrodes at a certain point, provide partitions 55 in the channels of some of the letters at certain

points, to suitably direct the current and also provide jumper channels or shunts in other letters.

In letters of the alphabet, such as C, G, I, J, L, M, N, S, U, V, W and Z, uniform illumination can be had by connecting an electrode at each 5 end of the letter, for in such a case, each letter is in the nature of a continuous channel and without any branches with closed ends, or closed loop portions. Where the insignia as shown by way of example in Fig. 6 have a branch 10, with 10 a closed end, or a closed loop 11, by employing my invention, every portion of the letter can be illuminated. Taking the letter A, for example, one electrode 12 is inserted in the end of a branch 10, a partition 15 closes one end of the hollow 15 cross piece 16, another partition 15 closes the other end, a hollow shunt or jumper channel 18, in the back of the letter connects the lower end of one branch 10 with one end of the cross piece 16, and at the other end is the other electrode 20 17. By this construction there is only one path, through which the current passes and that path traverses every portion of the gas channel 13, of 25 the letter that is to be illuminated. The necessity for a construction of this character arises 25 out of the fact that if there are two independent channels through which the current may pass from one electrode to the other, it will pass through the shorter channel leaving the longer channel not illuminated. The arrows show the 30 direction of the current through the gas channel of the hollow glass letter. In the other letters, shown in Fig. 6, the same reference numerals 12 and 17, indicate the electrodes, 15 indicates the partitions, 18 the jumper channels and the 35 arrows indicate the direction of the current.

The glass letters are made in a mold press and comprise a front plate portion 19, raised portions 20, which give the configuration to the letter, hollow channels 13 back of the raised portions for 40 the illuminating gas and transverse partitions 15 that are molded an integral portion of the letter or channel. The back plate 21 is molded 45 separately and the jumper channels 18 are molded as an integral part of the plate. The back plate 21 and the front plate 19 while still hot are taken from the molding presses and placed one on top of the other, the temperature of the plates being such as that they fuse together at the contacting surfaces, thereby hermetically sealing the channels 13 and 18. The back plate 21 is provided with outstanding edges 22 between which the front plate 21 loosely fits and a bead 41 and co-operating groove accurately position the two 50 plates relative to each other. The cooperating 55

bead and groove also assure a perfect fusion between the plates.

In securing the electrodes in position, I find it advantageous to insert the glass tubes 23 during the molding operation of the back plate 21. The tubes 23 are suitably supported in the mold and the glass of the plate tightly molded around them. Thereafter the electrode shells 24 are inserted in position in the tubes, which are closed by squeezing the ends of the tubes around the stem 25 of the electrodes. In order to hold the opaque plates 26 in position, apertures 21 may be molded in the front plate, the plates 26 being held in position by the bent over metal strips 28. It will be understood that the remaining portion of the face of the unit or sign, that is not to be illuminated, will be covered by another metal plate 29.

The rear face of the back plate 21 may be silvered in order to reflect the rearward radiation toward the front and increase the efficiency of the illumination. The front face of the letters may be coated with translucent enamel of such color and quality as to give the desired optical effect.

25 The connecting terminals 30 are connected with the electrodes 24 through the leads 31 passing through apertures 32 in the plate 1.

By molding a partition 38 throughout the length of the gas channel, as shown in Fig. 7, to provide 30 two separate channels, each with its own electrodes and circuits, different colored gases may be introduced into the separate channels.

The channels in the letters will be evacuated and then filled with the illuminating gas through 35 a suitable opening in the panel which will afterwards be closed by application of heat.

From the above description, it will be seen that I am able to produce molded glass insignia, with the necessary integral gas channels therein, including letters of all the various types, continuous, 40 branched and looped; that by molding the letters in two parts, I am enabled to form the necessary partitions. By placing a separate pair of electrodes in each letter, it becomes a unit that can 45 be readily used in the making of any kind of a sign.

I claim:

1. An illuminated molded glass sign comprising a front plate provided with an insignia, a 50 rear plate fused to the front plate, a hermetically sealed gas channel between the plates and behind the insignia for illuminating the insignia, a transverse partition molded in the gas channel to close it and a jumper channel molded in the 55 rear plate and in circuit at each end with the gas channel on opposite sides of the partition.

2. An illuminated molded glass sign comprising as a unit, an internal hermetically sealed channel, shaped to the outline of a character, for containing an illuminating gas, a transverse partition 60 molded in the channel to close it and a jumper channel molded in the unit and in circuit at each end with the gas channel on opposite sides of the partition.

65 3. An illuminated molded glass sign comprising a front plate of glass having molded in its back surface an open channel in the shape of a character and a transverse partition molded in the channel, a rear plate of glass having molded 70 in its front surface an open jumper channel, the open part of the character channel and the edge of the partition being disposed against the face of the rear plate and the open part of the jumper channel being disposed against the back of the front plate, the two channels being in circuit with 75

each other to provide a passage for illuminating gas, the two plates being fused together at their contacting faces, inlet and outlet openings for the flow of an electric current through the said channels, the channel forming the outline of the character having a plurality of differently directed portions, one portion being separated from the other by the partition and connected by the jumper channel, to make a continuous one way channel of the said portions between the inlet and outlet openings, whereby the circuit traverses every section of the passage.

4. An illuminated molded glass sign comprising a front plate of glass having molded in its back surface an open channel in the shape of a character and a transverse partition molded in the channel, a rear plate of glass having molded in its front surface an open jumper channel, the open part of the character channel and the edge of the partition being disposed against the face 15 of the rear plate and the open part of the jumper channel being disposed against the back of the front plate, the two channels being in circuit with each other to provide a passage for illuminating gas, the two plates being fused together at their 20 contacting faces, inlet and outlet openings for the flow of an electric current through the said channels, the channel forming the outline of the character having a plurality of differently directed portions, one portion being separated from the other by the partition and connected by the jumper channel, to make a continuous one way 25 channel of the said portions between the inlet and outlet openings, whereby the circuit traverses every section of the passage and means for aligning the two plates to bring the two channels in proper juxtaposition.

5. An illuminated molded glass sign comprising a front plate of glass having molded in its back surface an open channel in the shape of a character, a rear plate of glass with electrode 30 openings molded therein, the open part of the character channel being disposed against the rear panel to provide a passage for illuminating gas, the electrode openings being in communication 35 with the character channel, glass electrode tubes molded in the electrode openings, the two panels being fused together at their contacting faces into a unit.

6. An illuminated molded glass sign comprising a front plate of glass having molded in its back surface an open channel in the shape of a character, a rear plate of glass with electrode 40 openings molded therein, the open part of the character channel being disposed against the rear panel to provide a passage for illuminating gas, the electrode openings being in communication 45 with the character channel, glass electrode tubes molded in the electrode openings, the two plates being fused together at their contacting faces into a unit and means for aligning the two plates to bring the channel and openings into proper 50 juxtaposition.

7. An illuminated molded glass sign comprising a front plate of glass having molded in its back 55 surface an open channel in the shape of a character, and a transverse partition molded in the channel, a rear plate of glass having molded in its front face an open jumper channel, the open 60 part of the character channel and the transverse partition being disposed against the face of the rear plate and the open part of the jumper channel being disposed against the back of the front plate, the jumper channel being in circuit at each 65 end with the character channel and on opposite 70

sides of the partition to provide a passage for illuminating gas, the two plates being fused together at their contacting faces and inlet and outlet openings for the flow of an electric current through the said channels.

5. 8. An illuminated molded glass sign comprising a front plate of glass having molded in its back surface an open channel in the shape of a character, and a transverse partition molded in the channel, a rear plate of glass having molded in its front face an open jumper channel, the open part of the character channel and the transverse partition being disposed against the face of the rear plate and the open part of the jumper channel being disposed against the back of the front plate, the jumper channel being in circuit at each end with the character channel and on opposite sides of the partition to provide a passage for illuminating gas, the two plates being fused together at their contacting faces, inlet and outlet openings for the flow of an electric current through the said channels and means for aligning the two plates to bring the two channels into proper juxtaposition.

25. 9. An illuminated molded glass sign comprising a back plate and a front plate fused together on their contacting faces, a channel in the shape of a character in one of the plates, interengaging means between the two plates for aligning them so that they may be in proper juxtaposition when fused together, one of the plates having outstanding edges between which the other plate fits and a cooperating bead and groove on the plates to accurately position the two plates relative to each other and assure a perfect fusion between the plates.

30. 10. An illuminated molded glass sign comprising

ing a front plate of glass having molded in its back surface an open channel forming the outline of a character, having a plurality of differently directed and intersecting portions, means for converting the said portions into a continuous one way channel and comprising a rear plate of glass having molded in its front surface an open jumper channel connected at its ends to the said character channel, the open part of the character channel being disposed against the front of the rear plate and the open part of the jumper channel being disposed against the back of the front plate, the two plates being fused together into a unit and inlet and outlet openings for the flow of an electric current through all of the said channels.

35. 11. An illuminated molded glass sign comprising a front plate of glass having molded in its back surface an open channel forming the outline of a character, having a plurality of differently directed and intersecting portions, means for converting the said portions into a continuous one way channel and comprising a rear plate of glass having molded in its front surface an open jumper channel connected at its ends to the said character channel, the open part of the character channel being disposed against the front of the rear plate and the open part of the jumper channel being disposed against the back of the front plate, the two plates being fused together into a unit, inlet and outlet openings for the flow of an electric current through all of the said channels and means for aligning the two plates to bring the ends of the jumper channel into proper juxtaposition with the character channel.

WILLIAM B. PIPER.
